UNITED STATES PATENT OFFICE.

ERNEST LIPPERT AND JOSEPH AMMANN, OF MERIDEN, CONNECTICUT.

COMBINATION ASH, MATCH, AND CIGARETTE HOLDER.

1,184,465.

Specification of Letters Patent.

Patented May 23, 1916.

Application filed August 10, 1915. Serial No. 44,843.

To all whom it may concern:

Be it known that we, ERNEST LIPPERT and JOSEPH AMMANN, citizens of the United States, residing at Meriden, in the county of New Haven and State of Connecticut, have invented a new and useful Improvement in Combination Ash, Match, and Cigarette Holders; and we do hereby declare the following, when taken in connection with the accompanying drawings and the characters of reference marked thereon, to be a full, clear, and exact description of the same, and which said drawings constitute part of this application, and represent, in—

15 Figure 1 a side view of a combined ash, match and cigarette holder constructed in accordance with our invention and shown in closed position. Fig. 2 a top or plan view of the same in the open position. Fig. 20 3 a sectional view on the line *a—b* of Fig. 2, on an enlarged scale. Fig. 4 a broken sectional view on the line *c—d* of Fig. 3. Fig. 5 a sectional view on the line *e—f* of Fig. 3. Fig. 6 a sectional view on the line *g—h* of Fig. 3. Fig. 7 a sectional view of the parts shown in Fig. 6 in the closed position, Figs. 25 5, 6 and 7 being enlarged.

This invention relates to an improvement in combined ash, match and cigarette holders, the object being to produce a convenient device for carrying cigarettes and matches and providing an ash tray which may be folded into compact form for carrying in the pocket, the device being especially adapted 30 for travelers' use; and the invention consists in the construction hereinafter described and particularly recited in the claim.

In carrying out our invention, we form the tray in two sections 2 and 3, which together form a complete tray, the sections being hinged together at the center and adapted, when folded, to be locked together by a clasp 4. The meeting ends of the tray are formed respectively with flanges 5 and 45 6, the edges of which are rolled around a pintle 7 by which the two parts of the tray are hinged together; and mounted on the pintle 7 at desired points, are feet 8 and 9 to which are respectively connected a ciga-

rette holder 10 and a match holder 11. If 50 desired, a cigar cutter 12 may be connected at one side of the cigarette holder 10.

In order to maintain the cigarette holder and match holder in vertical position when the parts of the tray are open, a notch 13 55 is formed in one of the knuckles on one member of the tray, and a corresponding notch in the adjacent side of the next knuckle in the other section of the tray; and between these two knuckles the 60 foot 9 extends the sides of the foot correspondingly notched or cut away to register with the notches in the knuckles of the tray members so that the knuckles on the section will bear one against one side of the foot 65 and the other against the opposite side of the foot when the tray is open so as to hold the match-holder carried by the foot in a vertical position.

It will be understood that the cigarette 70 holder is mounted on the pintle 7 in the same way. It will also be understood that the depth of the tray is such that when the two sections are folded together, the cigarette holder and match holder will be inclosed as 75 in a box; and the device, when closed, readily carried in the pocket or traveling case. As herein shown, the corners 14 of the tray will be rounded to form supports for cigars or cigarettes.

80

We claim:—

A combined ash, match and cigarette holder comprising two tray members formed with upwardly projecting flanges, said flanges formed with hinged knuckles, adjacent knuckles on the two members reversely notched, a pintle extending through said knuckles and hinging the two trays together, a container formed with a foot connected with the said pintle between a 90 knuckle on one tray member and the adjacent knuckle on the other tray member, the sides of the foot notched to correspond to the notches in the knuckles of the tray members.

ERNEST LIPPERT.
JOSEPH AMMANN.
